Term of patent 14 years

(Cl. D49—1)

FIG. 1

FIG. 3

FIG. 2

FIG. 4

FIGURE 1 is a front perspective view of a clothes washer embodying our new design;

FIGURE 2 is a cross-sectional view thereof taken on the line 2—2 of FIGURE 1 in the direction of the arrows;

FIGURE 3 is a side elevational view thereof taken on a reduced scale; and

FIGURE 4 is a front elevational view thereof.

The broken lines representative of the lower portion of the clothes washer have been omitted in FIGURE 1 for convenience of illustration.

The side not shown is the same as the side shown. The rear is plain.

The dominant features of our design reside in the portions shown in full lines.

We claim:

The ornamental design for a clothes washer or similar article, substantially as shown and described.
